UNITED STATES PATENT OFFICE.

ORA A. COLBY, OF MANSFIELD, OHIO, ASSIGNOR TO WESTINGHOUSE ELECTRIC & MANUFACTURING COMPANY, A CORPORATION OF PENNSYLVANIA.

ELECTRIC FURNACE.

Application filed November 7, 1927. Serial No. 231,472.

My invention relates to furnaces and more particularly to furnaces heated by electrical resistors.

It is an object of my invention to provide, in a furnace of the above type, heating elements adapted to cover the floor and side-walls of the heating chamber thereof, which are removable as a unit therefrom.

In practicing my invention, I provide horizontally and vertically disposed resistance elements mounted for movement as a unit into and out of operative position within a furnace chamber, and adapted to substantially cover the floor and longitudinal side-walls thereof.

In the drawing,

Figure 1 is a view, in transverse vertical section, of a furnace embodying my invention, and

Fig. 2 is a view in longitudinal vertical section, taken on the line II—II of Fig. 1.

Referring more particularly to the drawings, a furnace embodying my invention comprises side walls 2, roof 4, and bottom 6, of suitable refractory heat-insulating material. One end of the furnace chamber thus defined is closed by a refractory wall 8 provided with an opening to facilitate the charging and discharging of the material to be heat treated.

The opening is normally closed during the heating operation by a removable door 10 in the usual manner. The opposite end of the furnace chamber is closed by a removable wall 12 as hereinafter described.

Heating of the furnace is effected by means of performed, sinuously wound, electrical resistance elements 14 adapted to be disposed to cover the floor and side walls of the furnace chamber, and suitably connected to a source of electrical energy (not shown).

The means for supporting the heating elements within the furnace chamber comprises a horizontally-disposed frame 16, substantially co-extensive with the floor of the furnace, and vertically extending frames 18 and 20 secured to the upper face of frame 16 adjacent to the longitudinal edges thereof. The frames 18 and 20 are substantially co-extensive respectively with the faces of the longitudinal side-walls of the chamber, so that, with the frames assembled and in operative position within the furnace chamber, the floor and longitudinal side-walls thereof are substantially covered.

Any well known means for maintaining the

frames in assembled relation may be employed, but I prefer, in the present embodiment, to weld the frames 18 and 20 to the base frame 16, and to provide tie-rods 22 adjacent to the roof of the furnace and secured to the frames 18 and 20.

Electrically insulating blocks 24 are secured within the frames 16, 18 and 20, adjacent to the longitudinal edges thereof, and are suitably recessed to receive and support the return bend portions of the convolutions of the resistance elements 14.

With the structure above described in assembled relation, it is clear that the resistance heating elements are securely maintained in the frames 16, 18 and 20, and the frames are rigidly secured together to constitute a unitary structure.

The resistor supporting structure is mounted for movement, with respect to the furnace chamber, by means of flanged wheels 28 journaled in the longitudinal faces of the frames 16 and depending plates 30 integral therewith. The wheels 28 are adapted to ride upon rails 32 extending into the furnace chamber in longitudinally extending recesses 34 formed in the furnace side walls.

The removable wall 12 is secured to the movable resistor support by means of a depending angle plate 34 secured to a lateral edge of the frame 16 and adapted to engage the lower edge of the wall 12 in supporting relation. Additional means for securing the wall 12 to the resistor support comprises angles 36 extending through the wall and suitably secured to the frames 18 and 20 adjacent to the tie-rods 22. The wall 12 is thereby rigidly secured to the removable resistor support and movable therewith. Slots (not shown) are cut in the lower edge of the wall 12 and plate 34 to interfit with the rails 32 with a minimum of clearance, so that with the resistor support in operative position the wall 12 substantially completely closes the end of the furnace chamber.

In operation, if access is desired to the furnace chamber to make necessary repairs to the walls thereof, or if renewal of the heating element is necessary, the resistor support and wall 12 are moved as a unit to the left of the position shown in Fig. 2, out of the furnace chamber. Free access may then be had to the interior of the furnace, if desired. On the other hand, if the heating element is defective, the time lost in the renewal thereof

is reduced to a minimum, since the parts will cool relatively rapidly in the air to a point where manipulation thereof is possible.

When the necessary renewal or repairs have been completed, the assembly is moved into operative position within the furnace chamber, and the heating elements may be energized.

While I have shown a charging opening 10 for the furnace in the end wall 8, the furnace may be operated as a car-bottom furnace, whereby the resistor support may be removed from the furnace and the work to be heat-treated placed thereupon and moved 15 into the furnace therewith. Further, it is obvious that the shape and dimensions of the heating element and furnace parts may be varied within wide limits and be within the scope of the present invention.

20 Various modifications may be made in my invention without departing from the spirit and scope thereof and I desire, therefore, that only such limitations shall be placed thereon as are imposed by the prior art and set forth 25 in the appended claims.

I claim as my invention:

1. In an electric furnace, the combination with resistance elements adapted to cover the

floor and side walls thereof, of means for supporting said resistors to permit the removal thereof as a unit from the furnace chamber, said means comprising a frame, a plurality of wheels journaled in said frame, and a track for said wheels.

2. A resistor support for an electric furnace comprising a base frame, vertically extending frames secured to the longitudinal edges thereof and means for mounting said frames for movement into and out of said furnace, said means comprising supporting 40 wheels journaled in said base frame, and means for guiding the movement of said support with respect to said furnace.

3. A resistor support for an electric furnace comprising a base frame, vertically extending frames secured to the longitudinal edges thereof and means for mounting said frame for movement into and out of said furnace, said means comprising rails extending into said furnace, and flanged wheels journaled in said base frame and adapted to cooperate with said rails.

In testimony whereof, I have hereunto subscribed my name this 25 day of October, 1927.

ORA A. COLBY.
